VENTILATING AND AIR CONDITIONING METHOD AND SYSTEM FOR INCLOSURES

Filed Aug. 2, 1927

UNITED STATES PATENT OFFICE

LEO L. LEWIS, OF PLAINFIELD, NEW JERSEY, AND ALFRED C. BUENSOD, OF NEW YORK, N. Y., ASSIGNEES, BY MESNE ASSIGNMENTS, TO AUDITORIUM VENTILATING CORPORATION, OF JERSEY CITY, NEW JERSEY, A CORPORATION OF NEW JERSEY

VENTILATING AND AIR CONDITIONING METHOD AND SYSTEM FOR INCLOSURES

Application filed August 2, 1927. Serial No. 210,164.

This invention relates to ventilation and air conditioning methods and systems for buildings or inclosures in which people congregate, such for example, as theaters, auditoriums, assembly halls, and the like places. In order to insure the comfort of people assembled in such places, in which at times large numbers of people congregate, various schemes have been devised for conditioning the air of such

10 buildings and admitting sufficient fresh air for the purposes of ventilation. Heretofore, the control of ventilation and atmospheric conditions in such buildings has been confined to the auditorium proper or main assembly room; or freshly conditioned air has been independently supplied directly to the auxiliary rooms; or separate or independent ventilating and air conditioning systems have been used for the main assembly room and for 15 the auxiliary rooms, such as the lobby or foyer through which the people pass to and from the main room, the lounge and projection rooms, etc.

It has also been usual in prior ventilating 20 and air conditioning systems to isolate the auditorium from the lobby or foyer and other auxiliary rooms, such as by doors often successively arranged. In fact, double doors between the foyer and the street have been the rule rather than the exception. These extra doors, or closed doors, between the street and the auditorium proper have been considered necessary or desirable, in spite of the well known fact that an open door or entranceway 25 is more inviting to patronage than a closed door, even though, as in large auditorium buildings, the architectural treatment very frequently calls for doors of massive construction which appear to be difficult to open.

30 With such prior systems, every entrance to and every exit from the assembly room has also been a continuous source of annoyance. For example, it has been customary in such ventilating and air conditioning systems to 35 exhaust an amount of air equal to that supplied, leaving no excess supply to balance the stack effect caused by the column of relatively warm or cool air enclosed in the assembly room. Such assembly rooms almost invariably have many openings in the top and other

parts of the structure through which, in winter, the warm air of the assembly room can escape, and the escape of this warm air causes the entrance of cold air through the various open doors and cracks in the lower parts of the theater. To check this entrance of cold air, some theaters use as many as four sets of doors between the street and the auditorium.

When, as in the summer time, the column of air in the assembly room or building is cooler than that outside, the stack effect is the reverse of that just described, and the cold air tends to flow out through the openings at the lower part of the room drawing in warm air through the openings in the upper part of the room.

When fresh air is admitted to a room, or mixed with air withdrawn from the room and the mixture returned to the room, the total quantity of air admitted to the room will be greater than the quantity of air withdrawn therefrom and returned, with the result that there will be created in the assembly room or auditorium, some increase in the atmospheric pressure therein, the extent of pressure increase depending upon the amount of fresh air which has been admitted relative to the air relieved from the room. It has been customary heretofore to relieve this pressure by discharging a quantity of the air from the room through suitable relief openings on the roof or at other remote places. The discharge of air from the room in this manner has been an economic loss, but since a certain amount of fresh air should be admitted for ventilating purposes, such loss has been considered unavoidable.

Attempts have been made to supply conditioned air to the grand foyer and other auxiliary rooms by the provision of a separate conditioning system, or the use of conduits for supplying freshly conditioned air directly therein. The provision of an extra air conditioning system, or extra pipes, or larger equipment necessary to handle a larger quantity of conditioned air, is relatively expensive for the small benefits obtained. The grand foyer or lobbies are also often provided with relatively high ceilings and the

circulation therethrough of any conditioned air admitted thereto has been difficult to accomplish in a simple or satisfactory manner.

One object of this invention is to generally 5 improve ventilating and air conditioning methods and systems for auditoriums and analogous places of assembly.

Another object of the invention is to provide an improved ventilating and air conditioning system for such places, with which 10 indrafts of unconditioned air may be avoided; with which the advantages of an open entranceway may be obtained; with which less or smaller operating equipment is required; with which the air discharged from 15 the auditorium or rooms is employed to commercial advantage; with which losses arising in ventilating and conditioning the air of such auditoriums will be reduced to a minimum; and with which control of the ventilation 20 and air conditioning is more uniform and dependable.

Another object of the invention is to provide an improved and efficient method and 25 apparatus for ventilating and conditioning the air of auditoriums and like places in which people assemble, with which the use of separate or supplemental ventilating and air conditioning apparatus for auxiliary 30 rooms such as the lobby is avoided; and by which the air movement and circulation in the auxiliary room or rooms is adequate to cause thorough diffusion and circulation of 35 the conditioned air entering the auxiliary room from the main room.

A further object of the invention is to provide an improved method and apparatus for 40 ventilating and producing desired atmospheric conditions in the foyer, lobbies or other auxiliary rooms of theaters, auditoriums and the like buildings, which will not encroach upon the space of the auxiliary room; which will not interfere with the architectural or 45 artistic ornamentation of the auxiliary room; and which will be relatively simple, effective, durable and inexpensive.

Various other objects and advantages will be apparent from the following description 50 of an embodiment of the invention, and the novel features will be particularly pointed out hereinafter in connection with the appended claims.

The accompanying drawing illustrates in 55 sectional elevation, and more or less diagrammatically, a theater or auditorium building having a main assembly room and a grand foyer or lobby communicating therewith and equipped with means in accordance with this invention for ventilating and providing desired atmospheric conditions in both the main room and foyer or lobby.

In the illustrated application of the invention, the main assembly room 1 may be that of a conventional theater or auditorium building 60 having a stage 2 at one end, and an auxil-

iary room, such as an entrance lobby or grand foyer 3 communicating with the other end of the main or assembly room. The auditorium or assembly room is substantially closed, that is, there are no doors or openings leading 70 directly to the outside air other than the emergency exits which are normally kept closed, but the foyer or lobby through which the people enter the auditorium is in communication with the assembly room, such as through one 75 or more suitable doorways 4. The lobby or foyer is provided with any desired number of doorways 5 through which people may enter or leave the building on their way to and from the auditorium or assembly room, and these doorways afford openings through which air can escape from the assembly room through the lobby.

The air of the main or assembly room 1 may be conditioned in any suitable manner and placed under an atmospheric pressure slightly in excess of that of the outside atmosphere and of the lobby, and this slightly greater pressure in the main assembly room causes a flow of conditioned air from the main or 90 assembly room through the doorways 4 or other openings into the grand foyer or lobby 3, and thence through the outer door openings 5 to the street.

The excess atmospheric pressure which 95 causes displacement of air from the main assembly room through the lobby or foyer may be created in any suitable manner. By way of example, the main or assembly room 1 may be supplied with conditioned air through 100 pipes 9 and 10 which discharge into different parts of the main assembly room through suitable discharge openings or devices 11. Such discharge openings are commonly in or near the ceiling, of the main room, and also just beneath the balcony if the room happens to be provided with a balcony. Air may be withdrawn from the main room through suitable openings 12 arranged in or adjacent the 105 floor or at other appropriate points, and communicating with a conduit 13, the balcony also preferably having openings 14 in or near its floor communicating with a conduit 15. The conduits 13 and 15 are connected to a common withdrawn air pipe or conduit 16 110 communicating with the suction side of a fan or air circulating device 17 and the pipes 9 and 10 are connected together and to the discharge side of the air circulating fan or 115 device 17.

A suitable air conditioning device 18 may be provided at a suitable point so as to remove moisture from or add moisture to air passing therethrough for supply to the auditorium. Such air conditioning devices are well known in the art and therefore a detailed description of the same is omitted in the interest of clarity. A mixing chamber 19 may be provided at the entrance end of the air conditioning device 18, and another mixing 120

chamber 20 may be provided between the air conditioning device and the intake side of the fan or blower 17. A heater 21 may be provided for the air, and for convenience may be arranged at the intake side of the fan or blower 17. The withdrawn air pipe 16 may be branched, one branch 22 leading to the mixing chamber 19, and another branch 23 leading to the mixing chamber 20, the two branches having damper or shutter devices 24 and 25 respectively, by which the proportions of air withdrawn from the main assembly room and passing through or bypassing around the air conditioning device 18 may be selectively varied.

Fresh outside air may be brought into the building through a suitable fresh air conduit 26 and this conduit may in turn be provided with a branch 27 leading to the mixing chamber 19, and another branch 28 leading to the mixing chamber 20. Thus, by suitably controlling the air flow through the branches 27 and 28, all of the fresh air may be passed through or bypassed around the air conditioning device 18, or any desired proportion of the fresh air sent through the air conditioning device, and the remainder bypassed. The branches 27 and 28 of the fresh air conduit may be provided with shutter devices 29 and 30 for controlling the relative amounts or proportions of the fresh air which are sent through or bypassed around the air conditioning device 18.

The particular type of air conditioning device 18 which has been illustrated by way of example is one of the spray type, the liquid for the same being circulated by a pump 31 and pipes 32, and the circulating liquid being cooled by suitable refrigerating apparatus 33 when refrigeration of the sprayed liquid is desired. The air heater 21 may be located, as shown, at the discharge end of the air conditioning device, or one or more heaters may be provided at any other suitable point or points of the air circulating system.

With such an arrangement, either the fresh air alone or the withdrawn air can be conditioned before delivery to the auditorium, or the withdrawn air may be mixed with any desired quantity of fresh air, and any proportions or combinations of withdrawn air and fresh air conditioned, so that the final mixtures of withdrawn and fresh air passing through the heater 21 and delivered by the circulating fan or blower and pipes 9 and 10 to the auditorium 17 will have any desired condition of temperature and humidity. In the illustrated application of the invention, it will be noted that all of the withdrawn air may be returned to the main or assembly room, and a selected quantity of fresh air also conducted therewith to the main room, or instead, only fresh air may be conducted to the main room and either the fresh air or the

withdrawn air or a mixture of both can be conditioned as may be required.

The addition of fresh air to the withdrawn air, or the sending of only fresh air to the main room creates in the main assembly room an atmospheric pressure slightly above that of the outside atmosphere, with the resulting displacement of air from the main or assembly room through the auxiliary room or rooms, such as the grand lobby or foyer 3, to the outside atmosphere, the amount of displacement being approximately the excess of the returned over the withdrawn air that is approximately equal to the amount of fresh air admitted. The air pressure in the main room in excess of outside atmosphere also prevents the entrance of outside air to the main room through any cracks, or loosely fitted doors, windows or like openings, regardless of outside atmospheric conditions, because there will always be some direct displacement of the air from the main room to the outside atmosphere through the cracks and like openings that are almost always present in a large building, as hereinbefore explained.

Air displaced from the main room and entering the grand foyer or lobby 3, for example through the door openings 4, will to some extent diffuse through the lobby or foyer, but inasmuch as the lobby is often provided with a high ceiling and frequently is quite large, the circulation and diffusion is not as rapid or complete as is usually required. Accordingly, independent circulating means may be utilized to thoroughly diffuse and circulate the air in the foyer or lobby.

For this purpose a circulating fan 34 may be utilized and preferably is disposed exteriorly of the lobby, such as below the floor. It may be connected at its intake side by a pipe 35, preferably to one or more points of the lobby, and connected at its discharge side by a pipe 36 to one or more outlets 37 in the ceiling or other suitable part of the lobby, which discharge outlets are spaced remotely from the intake openings of the pipe 35, so that the air withdrawn from the lobby and circulated by the fan 34 will be thoroughly diffused and circulated throughout all parts of the lobby. A branch pipe 38 may lead from the main room to the intake pipe 35, and the pipes 35 and 38 are controlled by dampers 39 so that the fan 34 can take the air either from the main room or from the lobby, as hereinafter explained.

Preferably each of the outlets of the pipe 36 into the lobby is provided with deflectors or tubes adapted to cause distribution of the ingoing air in various directions, so as to cause circulation of the air to all parts of the lobby. In a lobby or foyer where people are on their feet and free to move, it is usually not objectionable to blow the currents of air toward the people, if the air is discharged at

points removed from the people sufficiently to cause the currents or jets of air to spread and lose their objectionable velocity before striking the people.

- 5 In cases where it is desirable or necessary to normally keep the door openings 4 between the auxiliary rooms and the main room closed, suitable conduits (not shown) may be provided for connecting the main and auxiliary rooms, so that the air may be displaced through these conduits between the rooms, or if desired, the pipe 35 at the intake side of the circulating fan 34 may be connected to the main room, or the branch 38 may be connected therewith, as shown, to facilitate the displacement of the conditioned air from the main room to the auxiliary room, as well as cause diffusion and circulation of the displaced or excess air through the auxiliary room.

This improved system is distinctly different from prior systems in that instead of removing all of the excess air by means of an exhaust fan, and as a result more frequently than not causing an inrush to the assembly room of unconditioned air through the entrance door, the exhaust fan may be eliminated, and the resulting increased atmospheric pressure built up in the auditorium or assembly room by the addition of fresh air causes an outward flow of conditioned air through the auxiliary rooms and particularly so through the lobby or grand foyer. By the herein described system, this movement of conditioned air, which heretofore has been exhausted through the roof or other places where its benefits were all lost, is utilized as a source of conditioned air for the auxiliary rooms, particularly the lobby or foyer, thus eliminating the use of special apparatus for that purpose. In the case of large rooms, such as larger foyers or lobbies, particularly those having high ceilings, the conditioned air may be locally circulated therein as explained, to insure uniform conditions throughout those rooms, and the conditioned air from the lobby or foyer conducted out through the entranceway upon a public thoroughfare along which pedestrians or possible customers travel.

This outward flow of air through the entranceway effectively prevents the inflow therethrough of unconditioned air and therefore objectionable drafts or interference with the proper control of the atmospheric conditions in the auditorium or assembly room, and the auxiliary rooms, and in addition is now a valuable asset because in passing out through the entranceway, it serves as a silent, yet appealing advertisement to the public by directing their attention to the attractive atmospheric conditions within the theater or auditorium. Thus with this system, the heretofore wasted conditioned air is now utilized advantageously as a silent ad-

vertisement of the theater or auditorium. With such a system, the entranceway may be, and should be, kept open and thus one is able to take advantage of the psychological fact that an open door is more inviting to 70 patronage than a closed door, and an actual sample of the conditions within the theater or auditorium is far more convincing than verbal statements or pictures suggesting refrigeration. 75

It will be obvious that various changes in the details, which have been herein described and illustrated in order to explain the nature of the invention, may be made by those skilled in the art within the principle and scope of 80 the invention as expressed in the appended claims.

We claim as our invention:

1. The method of ventilating and providing desired atmospheric conditions in a substantially closed main room in which people congregate and in an auxiliary room communicating with said main room, which comprises withdrawing air from said main room, conditioning air for supply to said main room, forcibly delivering, by pressure differences said conditioned air with variable proportions of said withdrawn air and fresh air into said main room and displacing from the main room to the auxiliary room volumes of 95 the air thereof approximately equal to the fresh air delivered into the main room, and relieving air from said auxiliary room to permit of displacement of air thereto from said main room. 100

2. The method of ventilating and providing desired atmospheric conditions in a main room in which people congregate and in a smaller room communicating with said main room, which comprises withdrawing air from said main room, conditioning more or less of said withdrawn air and delivering forcibly by pressure differences said conditioned air with variable proportions of outside air into said main room and causing a displacement 105 of the air of said main room into said smaller room in amounts substantially equal to the proportion of outside air delivered to the main room, and relieving air from said smaller room to permit the entrance therein 110 of air displaced from said main room.

3. The method of ventilating and providing desired atmospheric conditions in a closed main room in which people may congregate and in an auxiliary room communicating with said main room, which comprises withdrawing air from said main room, concurrently supplying to said main room, conditioned air in a quantity greater than the withdrawn air to create in said main room an atmospheric pressure above that of said auxiliary room, whereby conditioned air will be displaced by pressure differences from said main room to said auxiliary room, and relieving the auxiliary room of air to cause 130

a movement therethrough of the displaced conditioned air.

4. The method of ventilating and providing desired atmospheric conditions in a closed main room in which people may congregate and in an auxiliary room communicating with said main room, which comprises withdrawing air from said main room, concurrently supplying to said main room, conditioned air in a quantity greater than the withdrawn air to create in said main room an atmospheric pressure above that of said auxiliary room, whereby conditioned air will be displaced by pressure differences from said main room to said auxiliary room, relieving the auxiliary room of air to cause a movement therethrough of the displaced conditioned air, and forcibly and locally circulating and diffusing the air in said auxiliary room to make the atmospheric conditions uniform throughout that auxiliary room.
